(57) **CLAIM**

The ornamental design for a chair, as substantially shown and described.

DESCRIPTION

FIG. 1 is an isometric perspective view of a chair, showing the novel design.

FIG. 2 is an exploded view of the chair shown in FIG. 1.

FIG. 3 is a top plan view of the chair shown in FIG. 1.

FIG. 4 is an elevated front side view of the chair shown in FIG. 1.

FIG. 5 is an elevated rear side view of the chair shown in FIG. 1.

FIG. 6 is an elevated left side view of the chair shown in FIG. 1; and,

FIG. 7 is an elevated right side view of the chair shown in FIG. 1.

The matter delineated in broken lines forms no part of the claimed ornamental design.

1 Claim, 5 Drawing Sheets
